(57) **CLAIM**

The ornamental design for a bottle closure, as shown and described.

DESCRIPTION

FIG. 1 is a perspective view of a bottle closure in accordance with our new design, shown in a closed configuration;

FIG. 2 is a top view thereof;

FIG. 3 is a front elevational view thereof;

FIG. 4 is a left side view thereof, the right side view being a mirror image;

FIG. 5 is a rear elevational view thereof;

FIG. 6 is a bottom plan view thereof;

FIG. 7 is a perspective view of the bottle closure of FIG. 1, shown in an open configuration;

FIG. 8 is a top plan view thereof;

FIG. 9 is a front elevational view thereof;

FIG. 10 is a left side view thereof, the right side view being a mirror image;

FIG. 11 is a rear elevational view thereof; and,

FIG. 12 is a bottom plan view thereof.
